tion of New York

Application June 18, 1951, Serial No. 15,580

Term of patent 7 years

(Cl. D58—9)

To all whom it may concern:

Be it known that I, Arnold Perlman, a citizen of United States of America, residing at Greenwich, in the county of Fairfield and State of Connecticut, have invented a new, original, and ornamental Design for a Bottle, of which the following is a specification, reference being had to the accompanying drawing, forming part thereof.

In the drawing

Fig. 1 is a top plan view of a bottle, showing my new design;

Fig. 2 is a front view; and

Fig. 3 is a side view.

I claim:

The ornamental design for a bottle, substantially as shown.

ARNOLD PERLMAN.
